Patented Dec. 20, 1927.

UNITED STATES PATENT OFFICE.

JOSEPH CARTELLI, OF HARTFORD, CONNECTICUT.

TRAFFIC SIGNAL.

Application filed June 7, 1926. Serial No. 114,056.

My invention relates to the class of devices that are employed for automatically directing traffic, and an object of my invention, among others, is the production of a device of this type that shall be simple in construction and particularly efficient in operation.

One form of device embodying my invention and in the construction and use of which the objects herein set out, as well as others, may be attained, is illustrated in the accompanying drawings, in which—

Figure 1 is a view in elevation of my improved signal in one of its forms.

Figure 2 is a similar view showing another form of the signal.

Figure 3 is a view, scale enlarged, illustrating the working unit embodied in my improved signal.

Figure 4 is a view in side elevation of said working unit.

Figure 5 is a view in end elevation of the same.

In the accompanying drawings the numeral 5 indicates the base of my improved signal that may be constructed of any suitable material and in any desired form and that may be provided with an opening closed by a door 6, the working unit of my improved signal being located within this case.

This working unit comprises a base plate 7 upon which the mechanism as a whole is supported and which base plate is secured in any suitable manner within the chamber in the base 5, the specific means of securing the base plate not being shown herein. A motor 8 is mounted upon the base plate, the shaft of the motor bearing a pinion 9 meshing with a gear 10 secured to a driving shaft 11

40 mounted in bearings in standards 12 secured to and rising from the base plate 7, there being one of these standards preferably located near each end of the shaft 11. A worm 13 on the shaft 11 meshes with a worm

45 gear 14 mounted on a vertical axis on a pedestal 15 secured to and rising from the base, said worm and gear having an actuating finger 16 projecting therefrom for engagement with pins 17 projecting from the

50 under surface of an actuating disc 18 supported on a shaft 19 mounted in bearings in a pedestal 20 secured to and rising from the base plate 7. The pins 17 are supported in the path of movement of the finger 16

55 so that, as the latter is revolved, it will engage one of said pins and thereby impart a step-by-step movement to the disc 18, in a manner that will be readily understood, it being noted that when the finger 16 is disengaged from one of the pins the next succeeding pin will be located in the path of movement of said finger in its next revolution. A spring detent 21 may be employed to engage notches 22 in the disc 18 to frictionally hold the latter against movement except when rotated by the finger 16

60 engaging one of the pins 17.

A stud 23 projects from the face of the disc 18 in position to engage slots in one member 24 of a Geneva movement of ordinary and well known construction, the other member 25 of said movement being secured to the face of the disc 18, and as shown in Figures 3 and 4 of the drawings, the member 25 being cut away as at 26, in a manner 70 common to these movements, to permit rotation of the member 24 when a slot therein is engaged by the stud 23, and as shown in Figure 3 of the drawings, it being understood that the member 24 is held against 80 rotating movement when the recesses 27 in the arms thereof are fully engaged by the circular periphery of the member 25.

The member 24 is secured to an indicating shaft 28 mounted in bearings in a bracket 29 rising from the base, said shaft being preferably hollow for the passage of electric wires to be hereinafter described.

From this description it will be noted that as the motor 8 is rotated a one step movement is imparted to the disc 18 at each rotation of the gear 14, and, in the construction herein shown, there being eight of the pins 17 a complete rotation of the disc 18 takes place after eight revolutions of the finger 16 and therefore a quarter rotation of the member 24 of the Geneva movement will take place at each eighth revolution of the finger 16. The shaft 28 may be supported, if desired, upon a step ball bearing 30, as shown in Figure 4 of the drawings.

It may be noted that the shaft 28 may be utilized in various ways for carrying my invention into effect. For instance: as shown in Figure 1, the shaft may be utilized for turning an indicating device in the form of an image 31 that may be displayed as a traffic officer, each quarter rotation of the shaft placing the image at angles of ninety degrees from its preceding positions. In

this form of the device a plate 32 is secured to the shaft 28 and the image 31 is secured to the plate. A light indicator 33 may also be supported on the plate 32 as upon a staff 34, which staff may be supported by the image. This provides two forms of a visual indicator in the device.

An audible indicator in the form of a whistle 35 may be employed, the whistle 35 being supplied with air as by means of a fan 36 secured to and driven by a shaft 37 connected by a pinion 38 and gear 39 with the shaft 11.

The emission of a current of air caused by the fan 36 may be controlled by a valve 40 secured at the end of a valve lever 41 operated by a valve finger 42 secured to the lever and projecting in the path of a valve actuating cam 43 secured to the surface of the member 25 of the Geneva movement. The whistle may be positioned to conduct the sound through a whistle outlet 44 in the base 5, and the image may be supplied with an imitation whistle 45, if desired.

An audible signal in the form of an electrically operated bell 46 may also be provided, this bell being secured to the shaft 28 if desired so that it will be located opposite the opening 47 each time the shaft comes to rest. (The showing of the bell in Figure 4 is diagrammatic). When the bell is used in connection with the image it may be located inside of the image, as shown in dotted lines in Figure 1.

The bell is electrically operated as by means of wires 48-49 extending to contacts 50-51 adapted to rest against the periphery of discs 52 secured to the shaft 28. The contacts 50-51 are secured to a rock shaft 53 mounted in a bearing rising from the base of the machine, a spring 54 being employed to rock the shaft in a direction to press the contacts 50-51 against the discs 52. Wires 55-56 connect the contacts 50-51 with any suitable source 57 of electricity, which source is also supplied by wires 58-59 to the motor 8.

A finger 60 extends from the shaft 53 in the path of movement of a cam 61 mounted on the member 25 of the Geneva movement.

From this description, taken in connection with the drawing, it will be noted that each time the shaft 28 is given a partial rotation the finger 42 will be engaged by the cam 43 and the finger 60 will be engaged by the cam 61 whereby both of the audible signals, including the whistle and the bell, will be sounded. A light 33 receives its energy through wires 63-64, conductors 65-66, and wires 67-68 from the source 57 hereinbefore referred to.

The arrangement of traffic signal thus set forth provides a number of advantages, amongst which is the fact that, in operation, it more nearly approaches the activities of

a human traffic officer, although the operation is entirely mechanism controlled. The control by an efficient traffic officer provides the best type of control, since it enables the latter to actually vision the traffic conditions and to provide for rapid movement of the traffic, one of the advantages being that he is able to quickly change the signal and thus definitely establish the new conditions with no delay. This is one of the difficulties which are present when a mechanical signal arrangement is substituted, due to the inability to provide the rapid semaphore movements within a mechanism which is being operated on a time-control basis. With signal lights as the control means, the rapid change can be provided by the location of contacts, but where the action involves a purely mechanical action as, for instance, the rotation of a semaphore shaft, the difficulty becomes apparent.

In the present invention, this condition is met by the general mechanism disclosed. For instance, assuming that the shaft 28 is designed to be shifted at intervals of two minutes (120 seconds), it will be understood that wheel 18 is rotated once during this period. However, this rotation is step-by-step with each increment of advance equal to one-eighth of a revolution (in the particular form illustrated), so that each advance includes an angular movement of wheel 18 a distance equal to 45°, with the time between advance movements equal to fifteen seconds. However, the time required to make the advance is but a fraction of this period of fifteen seconds, since it is controlled by the movement of gear 14 which, under this two-minute time assumption, would rotate once in the fifteen seconds, since one rotation of wheel 14 advances wheel 18 the distance of 45°. Since member 16 is active in this advance for an equal distance of travel—substantially 45° of the travel of wheel 14—it will be understood that the advance of wheel 18 from one step to the next, will be completed within this fraction of the movement of wheel 14, the result being that while the intervals of step-by-step movements of wheel 18 are approximately fifteen seconds, the actual time required in the advance is approximately two seconds (one-eighth of the time required for one revolution of wheel 14.) Hence, it is evident that the time required to shift the shaft 28 from position to position will be approximately two seconds, since such movement is completed during the period of activity of member 16 with one of the pins 17, thus approaching more closely the activities of the traffic officer at such time.

The advantage of this comes from the fact that the time required to change is too short to set up conditions of doubt in the minds of drivers. For instance, should the time of

change from one position to the other take a period of say twenty seconds, the semaphore or other signal would be in neither position during this period, and difficulties 5 in traffic can ensue from the fact that a driver may attempt to cross by considering this period a prolonging of the set period, and at the same time the intersecting driver may consider this period as anticipating, 10 and hence attempt to make the crossing. By the rapid change, the difficulty is greatly overcome since the signal shift is so short that a driver knows he cannot cross during the period, and hence, with the warning 15 given by the audible signal, no attempt is made to cross excepting when the signal is properly set.

With this rapid change condition, the audible signal is of importance, as is the 20 time during which it is operative. By placing the control of this timing on the male Geneva gear, accuracy is provided and at the same time the length of activity can be readily controlled. In the arrangement 25 shown the whistle cam 43 is shown as active, while the Geneva movement is just becoming active to rotate shaft 28. If cam 43 is positioned to sound the whistle as 16 becomes active to rotate the wheel 18, and the 30 whistle will become active as the turning of the semaphore begins. If the cam 43 becomes active in advance of actual movement of wheel 18 by member 16, the whistle will be active during the period of dwell of 35 wheel 18 before the actual change begins—in the time illustration above given, this activity would cover a period of fifteen seconds in advance of the turning of the semaphore and continue during a part or all of 40 that period. The same, of course, is true in connection with the bell signal. Both of these could therefore be considered as warning signals.

The arrangement not only has these 45 advantages but carries the additional advantage of having gear 14 travel at a fair speed—fifteen seconds per revolution in the above illustration as to time. A motor drive is essentially high-speed, with a small 50 motor, in order to obtain the power essential in rotating the signal, and the particular arrangement shown permits these conditions to be present without requiring a large casing to contain reduction gearing capable 55 of providing the desired time interval with a high-speed motor. The arrangement thus provides for a rather compact operating case such as will not materially interfere with the traffic.

60 In accordance with the provisions of the patent statutes I have described the principles of operation of my invention, together with the device which I now consider to represent the best embodiment thereof; but 65 I desire to have it understood that the device

shown is only illustrative and that the invention may be carried out by other means and applied to uses other than those above set out.

I claim—

1. An automatic traffic signal mechanism comprising a supporting means provided with a vertically disposed rotatable shaft, visual signal means supported and operated by said shaft, means for imparting rotative impulses to said shaft to alternately display desired signals to the traffic to be controlled, said last named means including a female Geneva gear fixed on said shaft and having a male Geneva gear cooperating therewith, a motor, means operated by said motor for imparting an intermittent step by step rotative movement to said male Geneva gear, and frictional means to prevent accidental turning of said male Geneva gear.

2. An automatic traffic signal mechanism comprising a supporting means provided with a vertically disposed rotatable shaft, visual signal means supported and operated by said shaft, means for imparting rotative impulses to said shaft to alternately display desired signals to the traffic to be controlled, said last named means including a female Geneva gear fixed on said shaft and having a male Geneva gear cooperating therewith, a motor, means operated by said motor for imparting an intermittent step by step rotative movement to said male Geneva gear, and frictional means to prevent accidental turning of said male Geneva gear, an audible signal, and controlling means for the signal operatively associated with said male Geneva gear for causing sounding of said signal upon each rotative impulse of the shaft.

3. An automatic traffic signal mechanism comprising a supporting means provided with a vertically disposed rotatable shaft, visual signal means supported and operated by said shaft, means for imparting rotative impulses to said shaft to alternately display desired signals to the traffic to be controlled, said last named means including a female Geneva gear fixed on said shaft and having a male Geneva gear cooperating therewith, a motor, means operated by said motor for imparting an intermittent step by step rotative movement to said male Geneva gear, and frictional means to prevent accidental turning of said male Geneva gear, a fan driven by said motor, a whistle operatively associated with said fan, and means normally rendering the whistle inoperative and operatively associated with the male Geneva gear to render the whistle operative upon each rotative impulse of the shaft.

4. An automatic traffic signal mechanism comprising a supporting means provided with a vertically disposed rotatable shaft,

visual signal means supported and operated by said shaft, means for imparting rotative impulses to said shaft to alternately display desired signals to the traffic to be controlled, 5 said last named means including a female Geneva gear fixed on said shaft and having a male Geneva gear cooperating therewith, a motor, means operated by said motor for imparting an intermittent step by step 10 rotative movement to said male Geneva gear, and frictional means to prevent accidental turning of said male Geneva gear, an audible signal, and controlling means for the signal operatively associated with said male Geneva gear for causing sounding of said signal upon each rotative impulse of the shaft, the operative connection between the signal controlling means and the male Geneva gear embodying a cam fixed to and 15 movable with said latter gear and an actuating arm on the controlling means disposed in the path of movement of said cam.

5. An automatic traffic signal mechanism comprising a supporting means provided 20 with a vertically disposed rotatable shaft, visual signal means supported and operated by said shaft, means for imparting rotative impulses to said shaft to alternately display desired signals to the traffic to be controlled, 25 said last named means including a female Geneva gear fixed on said shaft and having a male Geneva gear cooperating therewith, a motor, means operated by said motor for imparting an intermittent step by step 30 rotative movement to said male Geneva gear, and frictional means to prevent accidental turning of said male Geneva gear, a fan driven by said motor, a whistle operatively associated with said fan, and means normally 35 rendering the whistle inoperative and operatively associated with the male Geneva gear to render the whistle operative upon each rotative impulse of the shaft, said supporting means comprising a hollow base 40 having a sound emitting opening, and said

fan and whistle being mounted within said base.

6. In automatic traffic signal mechanism, wherein a vertical shaft carrying a signal structure is given an intermittent rotative 50 movement through a fixed angular distance at predetermined timed intervals to intermittently vary the signal relative to a direction of traffic approach, a constantly-driven motor, and means intermediate the 55 motor and the vertical shaft and rendered active by motor movements for producing the shaft movements at regularly-timed intervals, said means including a reducing gear assembly having a constantly-driven 60 gear and carrying an actuator, a rotatable element carrying a plurality of spaced members adapted to be successively engaged by the actuator to impart a step-by-step advance to the element by the actuator, and a 65 Geneva stop mechanism interposed between said element and the shaft with the female Geneva gear rendered active at intervals of time within which a plurality of step-by-step movements of the element have been 70 made manifest, the activity of the female Geneva gear movement being completed during the time period of activity of the actuator and one of the element members, whereby the movement of the signal shaft 75 between successive positions will be completed within a relatively short period of the time interval between successive positionings of the signal.

7. Signal mechanism as in claim 6 characterized by an audible signal adapted to be rendered active relative to the period of signal movement, means for rendering the audible signal active, and means for controlling the time of such activity, said latter 85 means including an element carried by and movable with the male member of the Geneva movement.

JOSEPH CARTELLI.
